CLAIM

The ornamental design for a navigation and docking light as shown and described.

DESCRIPTION

FIG. 1 is a front perspective view of a navigation and docking light showing our new design;

FIG. 2 is a rear perspective view of the navigation and docking light of FIG. 1;

FIG. 3 is a front elevation view of the navigation and docking light of FIG. 1;

FIG. 4 is a rear elevation view of the navigation and docking light of FIG. 1;

FIG. 5 is a left elevation view of the navigation and docking light of FIG. 1;

FIG. 6 is a right elevation view of the navigation and docking light of FIG. 1;

FIG. 7 is a top elevation view of the navigation and docking light of FIG. 1;

FIG. 8 is a bottom elevation view of the navigation and docking light of FIG. 1;

FIG. 9 is an exploded rear perspective view of the navigation and docking light of FIG. 1; and,

FIG. 10 is an exploded front perspective view of the navigation and docking light of FIG. 1.

The broken line(s) define the bounds of the claimed design and form no part thereof.

1 Claim, 6 Drawing Sheets
